CLAIM

I claim the ornamental design for a footing plug, as shown and described.

DESCRIPTION

FIG. 1 is a top perspective view of a first embodiment of a footing plug showing my new design;

FIG. 2 is a bottom perspective thereof;

FIG. 3 is a top plan view thereof;

FIG. 4 is a front elevational view thereof; the back elevational view is a mirror image thereof;

FIG. 5 is a left elevational view thereof; the right elevational view is a mirror image thereof;

FIG. 6 is a bottom plan view thereof;

FIG. 7 is a top perspective view of a second embodiment of a footing plug showing my new design;

FIG. 8 is a bottom perspective thereof;

FIG. 9 is a top plan view thereof;

FIG. 10 is a front elevational view thereof; the back elevational view is a mirror image thereof;

FIG. 11 is a left elevational view thereof; the right elevational view is a mirror image thereof; and,

FIG. 12 is a bottom plan view thereof.
